TURKEY SADDLE

William Henry Kennedy, San Bernardino, Calif.

Application March 23, 1937, Serial No. 132,587

11 Claims. (Cl. 119—143)

My invention is designated a turkey saddle and pertains to the type of invention known in the trade as "breeding jackets" or "breeding saddle aprons". As the special shape and type illustrated in my invention is intended more for use with turkeys, I have used the simple designation of turkey saddle.

Types of these saddles or jackets are illustrated for instance in the patent to Cook, No. 1,987,818, issued January 15, 1935 and Boardman, No. 1,949,004, issued February 27, 1934, also Smith, No. 2,006,118, issued June 25, 1935, the main characteristics of such patents and their use being known in the art.

Considerable objection has arisen particularly with those raising turkeys for the market in that the turkey saddles now on the market are unsatisfactory. A number of these saddles cause what are termed "wing sores", this being due to the wings being encircled by straps or the wings fitted through openings or holes in the saddle. Incidentally the fitting of the wing through an encircling tape or the like or through holes in the saddle, is relied on in a number of the prior constructions to hold the saddle properly in place on the turkey. Again in certain of the prior art, the saddles or jackets have been made of a strip of canvas or equivalent material which merely fits over the back and the sides of the turkey, the wings being positioned outside of the side coverings or apron part of the saddle. Therefore the apron covers the side of the turkey under the wings and the main saddle portion fits across the back of the turkey. Certain of these saddles of the prior art have pleats extending longitudinally so that the pleats will be located along the part where the back saddle part joins the apron portion. These pleats are unsatisfactory in that the pleats sometimes become turned so that they do not form a firm ridge extending longitudinally of the saddle.

An object and characteristic of my turkey saddle is that I use tapes which are stitched to the fabric such as canvas, forming the main portion of the saddle, these tapes extending lengthwise of the back portion of the saddle and parallel one to the other. They are positioned equidistant from a center line through the longitudinal center of the back portion of the saddle. A further characteristic is that the tapes are made of a folded strip of canvas usually somewhat heavier than that forming the saddle and apron portion proper. Such strip has a fold on one edge, and the two free edges of the strip are turned in, making four thicknesses of fabric adjacent one edge of the tape and two thicknesses adjacent the other edge. The material forming the tape is then stitched longitudinally by one or more line of stitches in order to develop a somewhat stiff and firm tape. This tape

is then stitched to the back portion of the saddle adjacent the line joining the apron part by a line of stitching with the inturned folded edge portions facing towards the longitudinal back center of the saddle. This causes the formation of two ridges formed by the tape, one being between the back portion of the saddle proper and the underside of the tape, the other ridge or edge being between the two free edges of the tape which are turned in and stitched together.

For the purpose of illustrating my invention as applied to different types of saddles, I show several different forms. The characteristics of one form is that the wing encircling tape is so attached to the saddle and made sufficiently thick and rigid, that it provides a flat surface in contact with the wing joint of the turkey next to the body. This flat surface distributes the pull and rubbing of the wing on the encircling tape thus provided for the wing and materially reduces the tendency towards what are termed wing sores. It has been found that wing sores are quite often developed by the type of poultry saddles now on the market and as the fowl have a habit of picking at the sores, an appreciable number so afflicted get their heads worked through the encircling strap or opening provided for the wings and strangle themselves, this sometimes causing quite a serious loss in a flock of fowl. In this simple type of my invention with the flat tape encircling the wing, I preferably form the wing encircling tape as a forward continuation of the tapes stitched to the back portion of the saddle. Therefore this may be made of one long tape. Another characteristic is that the binding on the lower edge of the apron is also a continuation of the wing encircling tape. This construction therefore provides for a relatively large wing opening, gives an improved fit of the blanket on the poultry and the saddle is maintained in its proper position and this without resort to any elastic portions in the tape or a tape or elastic member encircling the lower portion of the body or the breast of the fowl.

In another form of my invention, while I use the folded type of back tapes on the back portion of the saddle, I provide soft flat tapes which at the front cross over each other and thus provide a space between the forward edge of the saddle and the cross over of the tapes or straps for the neck of the turkey. The continuation portion of the straps or tapes connected to the forward edge of the apron part provide for the wings and thus when the wings are properly thrust through these side portions of the overlapped tape forward of the front edge of the apron part, the wings as they normally rest along the side of the fowl, hold the apron part of the blanket securely in position. This con-

struction materially reduces the danger of wing sores and is sufficiently loose across the upper part of the breast of the fowl that it does not annoy or worry the bird.

5 A further simple form of my turkey saddle is made from canvas shaped to form the back and apron portions, the apron portions having openings or cutouts through which the wings are inserted. However in the prior art it has been the 10 custom in this type to provide a binding at the edge of these wing openings. Such binding strips develop a relatively stiff and somewhat sharp edge which causes the so-called wing sores. When 15 these sores develop with this type of saddle, as the turkeys have a habit of picking at such sores, there is considerable loss through strangulation of the birds getting their heads thrust through the 20 openings and not being able to remove their heads from such openings at the wings and thus become strangled.

With my saddle, at the wing openings and the forward portion of the saddle, I preferably make this of two or sometimes more thicknesses of fabric whereas the main portion of the saddle is only 25 one thickness. The openings are then left with a rough edge from the cutting of the material and encircling stitches are positioned outwardly from the edge. Thus due to the two or three thicknesses and the rough or soft edge, there is little 30 danger of the binding of the wings through these openings developing wing sores. Another characteristic of this type of saddle is that the back portion which fits adjacent the neck has a decided 35 concave curve extending well back from the forward edge of the wing openings so that this type of saddle does not bind on the back of the turkey's neck. The usual type of binding may be used on the edge. This type of saddle also has the characteristic tapes stitched to the back portion 40 and running rearwardly from the wing openings, these tapes being parallel.

My invention is illustrated in connection with the accompanying drawings, in which:

45 Fig. 1 shows the saddle having the construction of Fig. 2 illustrated in place on a turkey.

Fig. 2 is a developed plan of the saddle illustrated in Fig. 1, this having the characteristics of the tapes attached to the back being continued and forming a binding for the bottom edges of 50 the apron and the rear of the back portion and also with the forward edges of the apron part forming loops or openings for insertion of the wings.

Fig. 3 is a vertical section through the saddle 55 at substantially a mid-section illustrating the approximate shape when in place on a turkey.

Fig. 4 is a detail section on the line 4—4 of Fig. 2 in the direction of the arrows to show the construction and attachment of the longitudinal 60 tapes to the back portion of the saddle.

Fig. 5 is a plan or developed view of a modified 65 or alternative construction to that of Fig. 2 illustrating the loops for the wings as being formed of crossed-over tapes which form an extension of the binding on the lower edge of the apron and the forward edge of the apron section of the saddle. In this construction the crossed-over 70 tapes are positioned on the forward part of the breast of the turkey.

75 Fig. 6 is a plan or developed view of a third alternative or modified form of saddle in which circular openings or perforations are provided for the wings, this illustrating a construction with the tapes on the back portion extending longitudi-

nally from the wing openings and the wing openings having a soft inner edge.

Fig. 7 is a longitudinal section on the line 7—7 of Fig. 6 in the direction of the arrows illustrating the manner of forming a soft edge of the circular 5 opening for the wings.

Referring first to the construction of Figs. 2, 3 and 4, the saddle is formed of a complete single thickness of fabric, such as canvas. This may be considered as having a back or central portion 11 10 and side aprons 12, the aprons being similar on each side. A straight transverse forward edge 13 of the back portion is preferably a selvage edge of the canvas. The lower edge 14 of the aprons and the rear edge 15 of the back panel 11 are made in 15 a sweeping continuous convex curve. There are also transverse forward edges 16 on the apron parts, these having a concave curve 17 merging with the transverse end 13. A strip of overlapped binding 18 is stitched to the edges 16 and 17 and 20 forms a somewhat soft forward edge.

The wing openings or loops 25 are formed by a somewhat stiff and flat tape 26 which extends forwardly from the front edge 13 and then follows a curve indicated at 27 to the junction point 28 25 of the binding tape 18 and the forward portion of the lower edge of the apron section. The lower edge of the apron and the rear edge 15 of the central panel have a folded hem 29. They also have a binding 30, this being a continuation of the 30 tape 26 which follows the curve of the lower edge of the apron and the back portion 15 of the center panel 11.

An important characteristic of my invention resides in the longitudinal tapes 35. These are 35 shown in detail in Fig. 4. The tape is made up and consists of a strip of fabric such as somewhat stiff canvas having a reverse fold 36 which forms one edge and two turned-in hem folds 37 and 38. The edges of the hem folds indicated 40 at 39 extend preferably more than one-half way towards the edge 36, that is, considering the full width of the tape. Such width is indicated by the measurement line 40. Stitching 41 and 42 secures the folded strip to form the tape and also to 45 attach such tape to the back portion of the saddle approximately along the line where the apron sections 12 extend downwardly when the saddle is fitted on a turkey. This construction develops a tape having the characteristic of a single edge 50 36 facing downwardly when the saddle is in position on a fowl and the two edges 37 and 38 positioned upwardly or facing towards the center of the back panel 11. On account of the portion of the tape between the stitching 41 and the two 55 edges 37 and 38 being flexible, these two edges may become slightly spaced apart leaving an inner space 43 between the back panel portion 11 and the lower hem 44 and an upper space 45 between the hem part 44 and the outer hem 46. 60 These may therefore be considered as forming longitudinal ridges along the turkey saddle substantially parallel to the center line of the back.

The preferred manner of making the wing 65 openings or loops 25 is by forming the abutment tapes 35, the forward part of the loops 26 and the binding 30 all from the same tape. This may be formed of a rather long tape, the two ends being indicated at 47 and stitched underneath the binding tape 30 at the rear end 15 of the back 70 panel 11. There is a slight approaching curve 48 in these tapes where they merge with the binding 18 on the front edge portions 16 and 17 of the apron portions of the saddle. This tape as it is made up is somewhat stiff and hence the forward 75

portion 26 is maintained somewhat flat and is sufficiently wide so that any pressure or pull adjacent the inner joint or the turkey wing distributes the pressure or pull and thus materially reduces the danger of forming wing sores. Also the edge formed by the binding 18 which fits back of the inner wing joint also reduces the danger of forming sores or the like. It will be noted that by this construction of saddle the wings fitting 10 through the wing openings or loops 25 and the wings extending rearwardly on the outside of the apron part are the only means for keeping the saddle properly on the fowl. However as these saddles are made in different sizes they 15 give a neat fit throughout a considerable range of weight of the fowl. Another characteristic of this invention is that the forward edge 13 of the back panel being a selvage edge is somewhat soft and as this passes over the back of the neck 20 of the turkey, it does not have any pulling action which might cause a sore. This forward edge 13 is also spaced rearwardly from the front portion of the wing loops when the device is in use so that the fowl may stretch its neck upwardly without causing a binding action along the selvage 25 edge 13.

In the construction illustrated in Fig. 5 the saddle has somewhat the characteristics of that of Fig. 2, there being a central panel 60 and side 30 aprons 61 having the built up tape 62 stitched on the fabric and extending parallel to the center line of the back. This tape is made up in the same manner as illustrated in Fig. 4 and positioned on the saddle the same way. In this construction the front edge 62' of the back part preferably has a tape binding 63. The front edge 35 of the apron sections indicated at 64 are cut back on a concave curve from the corner 65 at the front of the back panel and the lower edge 66 of the apron and the rear edge 67 of the back panel are formed in a sweeping curve except that the rear edge 67 is preferably transverse to the back panel.

I form two side wing openings 10 and a centrally positioned neck opening 11 by intersecting 45 tapes. These are preferably binding tapes which are left flat at the intersections. Thus the tape forms a binding 12 extending around the convex edge of the apron section across the rear end 67 of the center panel and has stitching 13 extending slightly forward of the outer corner 14 at the bottom of the aprons and the forward edge 64. At the termination of the stitching 13 the tape 50 is flat at its full width forming a soft tape section 15 which extends in what may be considered as a concave curve 16 and forms a binding 17 extending from the ends of the binding 63 around the edge 64 at the forward part of the apron 61. The stitching 18 extends forwardly of the tape 55 63 for a short distance. The tape portion 11 may have a slight forward extension 19 worked into the stitching 13. It will be noted therefore that these two soft tapes intersect at the overlap 80.

When this saddle is placed on a fowl the neck 65 extends through the opening 11 forward of the binding 63 and then overlap or cross part 80 is below the neck and well forward on the breast part of the turkey. The binding 17 is underneath 70 the wings and the tape 15 follows the front portion of the inner wing joint. As the wings extend rearwardly along the side apron 61, the saddle is maintained in place and has no construction for binding either on the neck or around the wings 75 which might cause wing sores.

In the construction of Fig. 6 the saddle is made of a complete strip 90 of canvas or the like and has a center or back panel 91 with side aprons 92. At the forward portion there is an under-layer of canvas 93 secured to the upper strip by 5 transverse stitching 94. The forward portion of the back panel indicated at 95 has a concave curve and is thus set back from the forward portion 96; that is, forward of the wing openings 97. This recessed portion 95 is to provide a comfortable fit at the back of the neck. 10

A binding 98 extends completely around the saddle, that is, across the part 95, around the lower edge of the apron sections 92 on the rear end of the back panel 91. There are also two stiff 15 and somewhat heavy tapes 99 made in the same manner as illustrated in Fig. 4 extending longitudinally on each side of the back panel from the wing openings. 20

The construction of the wing openings 97 is 25 illustrated particularly in Fig. 7 in which the circular line of cut of the fabric is indicated at 100, this being through the two thicknesses, that is, the upper canvas 90 and the lower transverse strip 93. A circular stitch 101 extends around the opening concentric thereto and spaced from the opening a distance indicated by the measurement line 102. The forward end of the thick 30 tapes 99 may be caught by this stitching and the rear end of such tapes is attached to the binding 35 tape 98. This construction of the wing opening forms a soft edge for encircling the inner wing joint between the circular cut edge 100 and the stitch 101. This part without any binding frays 40 and leaves a number of loose thread ends which form a soft and pliable encircling margin for the wings. In this construction the wings extending through the openings 97 hold the saddle in place, the wings extending along the apron 92. This construction brings the longitudinal tapes 99 in substantially the same relation to the aprons as in the constructions of Figs. 2 and 5 having the similar tapes and substantially the longitudinal line joining the back panel and the aprons. 45

Various changes may be made in the details of 45 the construction without departing from the spirit or scope of the invention as defined by the appended claims.

I claim:

1. A saddle for poultry formed of a flexible 50 fabric and having a central back panel and depending side aprons when the saddle is in position on a fowl, the lower edge of the aprons having a convex curve, the forward edge of the side aprons having substantially a concave curve, a 55 pair of parallel tapes secured to the top of the saddle and positioned substantially equi-distant from the center line of a back panel, said tapes being adapted to form two parallel ridges between the back panel and the apron portions, 60 there being secondary tapes extending forwardly from the tapes on each side of the back panel, said secondary tapes extending to and being secured at the lower edge of the side aprons at the front portion thereof, said secondary tapes with the concave curved edge of the side aprons forming wing openings whereby when the saddle is in position on a fowl the wings extend outside and longitudinally of the side aprons. 65

2. A saddle for poultry as claimed in claim 1, 70 said secondary tapes formed as a continuation of the tapes secured to the saddle on each side of the center panel and extending in a forward direction with a reverse turn and having the rear portion secured to the lower edge of the 75

apron and forming a binding along such lower apron edge.

3. A saddle for poultry formed of a flexible fabric and having a central back panel and depending side aprons when the saddle is in position on a fowl, the lower edge of the aprons having a convex curve, the forward edge of the side aprons being set rearwardly from the forward edge of the back panel and having substantially

10 a concave curve, tapes binding the forward edge of the aprons, the bottom edge of the aprons and the back edge of the back panel, and a pair of tapes extending forwardly from the forward portion of the back panel at the connection with 15 the taped front edges of the aprons, each tape leading to and being connected at the corner formed by the front edge and the lower edge of the apron.

4. A saddle for poultry as claimed in claim 3, 20 a pair of parallel tapes characterized by being formed of a strip of fabric having a reverse fold at one edge and having two inturned edge portions forming the other edge, the tape being stitched to the top of the fabric at substantially 25 the junction line of the back panel and side aprons, the inturned portions of the tape facing towards the longitudinal center of the back panel and being adapted to spread apart to form a first ridge between the back panel fabric and the first 30 inturned edge and a second ridge between said first inturned edge and the outer inturned edge.

5. A saddle for poultry comprising a flexible fabric having a back panel and two side apron sections adapted to hang downwardly when in 35 position on a fowl, the lower edge of the aprons having a convex curve merging with the transverse rear end of the back panel, the forward edge of the aprons being positioned rearwardly from the forward edge of the back panel and 40 having substantially a concave curve, and a relatively stiff tape extending longitudinally on each side of the back panel and being stitched to the fabric of the saddle, such tape at its forward end conforming to the shape of the front edge of the 45 apron adjacent the front portion of the back panel, the said tape continuing in an inward turn and being attached adjacent the front portion of the back panel, the said tape continuing in a reverse turn and being attached adjacent 50 the lower edge of the aprons on each side, the forward edge of the aprons and the forwardly extending tape providing wing openings.

6. A saddle for poultry as claimed in claim 5, the tape extending longitudinally of the back 55 panel having a lower single edge and a plurality of upper edges stitched to flex outwardly to form a pair of parallel ridges on each side of the center line of a back panel.

7. A saddle for poultry formed of flexible fabric 60 having a back panel central portion and two side apron portions, there being two longitudinal tapes stitched to the fabric on each side of the back panel and adapted to form a ridge along each side of the said back panel, the forward edge 65 of the aprons extending rearwardly in a concave curve from the forward transverse edge of the back panel, the aprons having a lower convex curve, a binding on the forward edge of the aprons intersecting the tape on each side of the 70 back panel, a binding on the lower edge of the aprons and across the rear edge of the back panel, two attaching tapes, each extending from

the binding at the forward edge of the apron adjacent the forward edge of the back panel and leading to the binding on the lower edge of the opposite apron whereby the two attaching tapes intersect and form two wing openings and an 5 opening forward of the back panel for the neck of the fowl.

8. A saddle for poultry formed of flexible fabric having a back central panel and two side apron portions adapted to hang downwardly 10 when in a position on a fowl, the lower edge of the aprons and the rear end of the back panel having a convex curve, the forward end of the back panel being transverse and having a selvage edge, the forward edge of each side apron being 15 set back from the forward edge of the back panel and having substantially a concave curve with a substantially straight section at the junction with the lower edge of the aprons, a pair of relatively stiff tapes positioned parallel and equidistant from the longitudinal center line of the back panel and stitched at substantially the turn joining the back panel and the apron sections when in position on a fowl, the tape with the back panel forming a ridge on each side facing towards 25 the back panel, the said tapes having a continuation converging together at the forward end of the back panel and having a reverse turn with a twist, the tapes continuing on the lower edge and the rear end of the back panel and forming 30 a stitched binding.

9. A saddle for poultry formed of flexible fabric having a back panel and a pair of side aprons adapted to hang downwardly when in 35 position on a fowl, the front portion of the back panel and the aprons having a second strip of fabric stitched to the first strip and having a pair of circular openings spaced apart to form wing openings with stitches concentric to the center of each opening, the stitches being spaced from the opening, the front edge of the back panel having a concave curve extending well back between the said openings and joining with the front edge of the apron with a convex curve substantially concentric to each opening, the lower 40 edges of the apron and rear edge of the back panel having a convex curve.

10. A saddle for poultry as claimed in claim 9, and a pair of tapes positioned parallel and equidistant from the longitudinal center line of the 50 back panel, stitched to the top of the first fabric and forming longitudinal ridges facing towards the back panel, the said tapes intersecting the said openings for the wings.

11. In a saddle for poultry formed of flexible 55 fabric and having a back panel and side aprons adapted to hang downwardly when in position on a fowl, means to secure the saddle to a fowl, the saddle having a pair of parallel tapes positioned equidistant from the longitudinal center of the 60 back panel, each tape being formed of a strip of fabric having a reverse fold facing towards an apron and having the opposite edge with two in-turned hem folds, the tape of the hem folds being stitched to the fabric adjacent the line between the back panel and the apron, the hem folds facing towards the back panel and adapted to form an inner space between the back panel and the innermost hem and a second space between the innermost and the outermost hem.

70

WILLIAM HENRY KENNEDY.
